Inventor:

Orien P. Wallace,

By Hugh K. Wagner,
Attorney.

UNITED STATES PATENT OFFICE.

ORIEN P. WALLACE, OF ST. LOUIS, MISSOURI, ASSIGNOR, BY DIRECT AND MESNE ASSIGNMENTS, OF ONE-THIRD TO DOMINICK KULAGE, OF ST. LOUIS, MISSOURI, AND ONE-THIRD TO MONARCH METAL PRODUCTS COMPANY, OF ST. LOUIS, MISSOURI, A CORPORATION OF MISSOURI.

METAL WEATHER STRIP.

Application filed September 19, 1923. Serial No. 663,582.

To all whom it may concern:

Be it known that I, ORIEN P. WALLACE, a citizen of the United States, residing at the city of St. Louis, in the State of Missouri, have invented certain new and useful Improvements in Metal Weather Strips, of which the following is a specification.

This invention relates to weather-strips, and pertains more particularly to improvements in weather-strips especially applicable to window frames provided with sliding sashes.

Heretofore weather strips installed in new houses have ceased to function properly after they have been in use for some time, because of undue shrinkage of the window sashes. To remedy this defect is the principal object to this invention.

Another object is to provide greater depth for the meeting contacting surfaces, and thereby considerably increase the impedance to the flow of air between the said surfaces. Other objects and advantages will be apparent as the description proceeds.

In the accompanying drawings forming part of this specification, in which like numbers of reference denote like parts wherever they occur,

Figure 1 is a horizontal sectional view on the line 1—1 of Figure 2, of a window frame and sash to which the weather-strip of this invention has been applied; and

Figure 2 is a fragmentary vertical sectional view taken on the irregular line 2—2 of Figure 1.

A window frame 1 has the conventional parting bead 2 between the lower-or-inner-sash runway 3 and the outer-sash runway 4, and also has the inside bead 5 for confining the sash 6 within proper bounds. The window sash 6 is of the usual type and contains the glass pane 7 secured to the sash 6 by the bead 8.

In equipping a window with this invention, the parting bead 2 is removed and part of its side 9 and its rear 10 are planed away to form an L-shaped seat 11, terminated by shoulders 12, for the reception of the weather-strip 13 of substantially Z-shaped cross-section, and preferably of metal. The

inside bead 5 is removed for planing a recess 14 on the inner half of its rear to provide a seat for the resilient strip 15, which is preferably of sheet bronze. The sash 6 is then removed for cutting a deep and narrow longitudinal slot 16 in each of its narrow sides 17, approximately three-eighths of an inch from the outside face 18 of the sash 6, and planing a recess 19 of less depth in each of its narrow sides 17 between the slot 16 and the outside face 18 of the sash 6. Another weather-strip 20, of L-shaped cross-section, and preferably of metal, has a wide flange 21 and a narrow flange 22. The wide flange 21 is of such thickness as to make a slidable but sufficiently air tight fit in the slot 16. Flange 21 is provided with transverse slots 23. Flange 21 is inserted in the slot 16, so that flange 22 extends outwardly, and pins 24 are driven through the frame across the slot 16 and through the slots 23. The pins 24 co-operating with the slots 23 permit lateral movement of the strip 20, but prevent longitudinal movement of the said strip in the slot 16. Parting bead 2 and strip 13 are next placed in position in the frame 1, the flange 25 and the web 26 of strip 13 being clamped and held between the bead 2 and the frame 1, the bead 2 being fastened in the usual manner. In this position flange 27 of strip 13 is parallel to and spaced from the bottom of runway 3. Window sash 6 is now replaced, care being taken that flange 22 passes between the bottom of runway 3 and the flange 27. Strip 15 is now inserted with its edge portion 28 passing between the flange 22 and the runway side 3. Strip 15 has the portion 29 adjoining its edge 30 bent at a slight angle at 31, so that when bead 5 is fastened to the frame 1 in the usual manner, the portion 29 of the strip 15 is clamped in its seat 14 between bead 5 and frame 1, and the edge portion 28 brought to bear resiliently against the flange 22 of the weather-strip 20, and forces the flange 20 against the flange 27.

The usual type of weather-strip 32 may be used at the sill 33 of the frame 1, and fits in the usual slot 34 in the bottom 35 of the window-sash 6. As shown the strip 32 is

thinner than the slot 34, and at its end portion 36 it makes what is merely a line contact with the sides 37 of the slot 34. On the sides of the window, however, such a strip 5 would leak with too much shrinkage of the window sash.

It is manifest, however, that no such leakage can occur with the improved type of weather-strip herein described, since all contacting surfaces are of large area or great depth, and furthermore the lateral movement of the strip 20 in the sash 6 takes care of any undue shrinkage.

I claim:

15 1. The combination with a window-frame and a sash having a longitudinal slot in its narrow side, of a weather-strip having an L-shaped cross-section, one flange of which is slidable laterally in the said slot, and the 20 other flange of which is spaced from the said narrow side, a second weather-strip secured

to the said window-frame and situated between the said narrow side and the said other flange, and resilient means for pressing the said other flange against the said 25 window-frame strip.

2. The combination with a window-frame and a sash having a longitudinal slot in its narrow side, of a weather-strip having an L-shaped cross-section, one flange of which is slidable laterally in the said slot, and the other flange of which is spaced from the said narrow side, a second weather-strip secured to the said window-frame and situated between the said narrow side and the said other flange, and a resilient strip secured to the window frame and pressing against the said other flange of the said L-shaped 30 weather-strip.

In testimony whereof I hereunto affix my 40 signature.

ORIEN P. WALLACE.
